ABSTRACT OF THE DISCLOSURE

A method of manufacturing condensers having discharge elements which includes forming a conductor into a U-shaped element with a dielectric material such as porcelain between the arms of said element and dipping the curved portion of the U-shaped conductor and at least a portion of the dielectric material into a bath of hardenable insulating material such as a thermosetting resinous material for a variable but predetermined distance so as to thoroughly coat the portions immersed and cement them together. After the resinous material is hardened, the curved portion of the U-shaped element and resinous material adhering thereto is cut off to divide the conductor into two separate electrodes having exposed end portions separated laterally by the dielectric material.

The present application is a continuation of application Ser. No. 604,859 filed Dec. 27, 1966.

This invention relates to a method of manufacturing plate condensers having discharge elements as disclosed in U.S. application Ser. No. 604,859 filed on Dec. 27, 1966, by present applicants, the present application being a continuation thereof and its manufacturing methods.

In a conventional condenser having a discharging gap, a part of each condenser electrode itself formed thinly on the dielectric of the condenser has been used as discharging element. For example, silver electrodes have been formed in the end part of element of a cylindrical condenser so that, when an abnormal voltage is impressed there, a discharge may be made and thereby a characteristic of recovery may be soon obtained after the discharge. However, in such condenser, if a discharge is repeated, the thin silver electrodes near the discharging parts will be destroyed by the discharge and will be apt to be deformed and the flashover voltage will fluctuate, so much as to be higher than 20% after 800 discharges. Thus it is difficult to obtain a uniform quality of discharge element and the life of the condenser is short. It has been desired to solve these defects as early as possible.

The present invention is an improvement of a conventional condenser.

An object of the present invention is to form a stable discharging part in a plate condenser having a discharging gap.

The present invention relates to a method of manufacturing a structure comprising a dielectric of a plate shape, a pair of conductors of a band shape arranged above and below said dielectric in a close and flat contact with respective surfaces of the latter so as to be a pair of electrodes, and an insulating material layer surrounding the dielectric and electrode portions of the conductors so as to hold them integrally.

FIG. 1(A) is an elevation of a plate condenser having discharging elements according to the present invention.

FIG. 1(B) is a side view of the same.

FIGS. 2(A) and 2(B) are views for explaining a method

2

of manufacturing a plate condenser of the present invention.

FIG. 3 is a view showing the present invention as used.

A plate condenser having discharging elements embodying the present invention shall be explained in the following. In FIGS. 1(A) and 1(B) showing a plate condenser having discharging elements according to the present invention, 1 is a dielectric element made preferably of a porcelain. Such porcelain had better be strongly sintered at a high temperature and is preferably of titanium or rutile, barium titanate or any alkaline-earth titanate, alumina, forsterite or steatite. Further, the porcelain element 1 should preferably be smooth on the surface and may be painted on the surface with an ordinary glaze. A band conductor 3 is formed in the form of a U on said element 1 as shown in FIG. 2 so as to hold the dielectric 1. After the conductor 3 having extensions 3a and 3b at both its ends is inserted into cut grooves 16 in a jig 12 so as to be fitted to the jig, the element 1 held with the conductor 3 is dipped into a bath of insulating paint 2 contained in a vessel 13. Here 7 is a limiter for regulating the length to be painted in the longitudinal direction of the element 1. Bolts 8 are screwed into said limiter so as to adjust the position of the limiter.

When heated, the paint 2 deposited on the element 1 of the condenser will strongly hold the conductor 3 and element 1 and conductor 3 will be strongly closed each other. The paint 2 is preferably of a material to be solidified by heat as a vehicle. For example, if a mixed thermosetting epoxy-phenol resin containing a hardener is used, the conductor 3 will be able to be closed against the element 1 at a low heating temperature. The conductor 3 is made preferably of silverplated copper but may be made of a brass, aluminum or iron sheet. The enlarged surface parts 5 of the band conductors 3 holding the dielectric element 1 between them serve as the electrode parts of a condenser. The width and shape of the conductor parts 5 are selected in response to the required electrostatic capacitance. Further, the paint part 10 and the conductor 11 at the end adjacent the closed end of the U are cut off with a diamond cutter 9 or the like along the line a-b. As the element 1 forms a part of the cross-section 4 excepting the painting part 10, said cross-section 4 which is removed the painting part 10 and conductor part 11 construct discharging electrodes having a stable discharging function.

Further, a part 15 not painted will be made on said element 1 by the limiter 7. The reason for its necessity is shown in the following. A plate condenser having discharging elements according to the present invention as used is shown in FIG. 3. The leading parts 13 and 14 of the conductor 3 are used as bent in a direction substantially at right angles to the dielectric element. In such case, the unpainted part 15 will have an advantage of increasing the insulating effect between the leading parts 13 and 14. The generation of coronas will be little.

As the discharging gap is determined by the thickness of the element 1, the discharging elements of the present invention can be formed to be high in the precision. Therefore, the flashover voltage is very uniform and can be varied by varying the thickness of the element 1.

Though one element is fitted to the jig in the embodiment of this manufacturing method, it is easy to work many at the same time. It is also easy to make a complex circuit part. Thus two or more discharging elements can be formed in the same element 1. In the present invention, it is not necessary to specifically silverplate the element 1.

The conductor 3 should be so smooth as to be easy to bring into close contact with the element 1. The shape of the conductor part 11 in the end part of the U-shaped

conductor 3 should conform to the thickness of the element 1.

Further, in the present invention, when the electrostatic capacitance of the condenser is of a large value, it will not be necessary to make the width of the conductor 3 large. The same silver electrode as in the conventional condenser technique may be formed in the element 1 and may be electrically connected with the conductor 3. As the conductor 3 is in the form of a flat plate, the radiation of heat is easy.

In such construction as in the above, when a forsterite porcelain plate of a longitudinal length of 10 mm., a lateral length of 7 mm. and a thickness of 0.5 mm. was used for the element 1 and a copper plate of a width of 2.5 mm. and a thickness of 0.2 mm was used for the conductor, a flashover voltage of 1500 v. DC was obtained.

Further, even when 5000 discharges were made, the rise of the flashover voltage was less than 10%. Substantially no variation of the electrostatic capacitance of the condenser was seen.

Though the discharge generated a corona once, it was soon converted to a spark discharge. The generation of coronas was very little. Even if heat was generated by a corona loss, the heat was seen to be dissipated into the atmosphere through the conductor 3.

Further, at not only impulse produced by a fault within the circuit but also a high voltage close to a direct current, an alternating current and a high frequency, a spark discharge will be easily generated and the delay of the spark will be so little as to be presumed to be less than 10^{-4} seconds. The voltage-time curve $V-t$ is substantially horizontal. Thus the electronic devices can be well protected.

The effects obtained by the plate condenser having the discharging elements of the present invention as described above can endure many discharges and give stable electronic circuits. Said condenser is very easy to make and can protect electronic devices while keeping the action of a condenser. Further, in the present invention, the flashover voltage is stable, complex parts can be easily made, the condenser can be made small and, as the conductor 3 can be made parallel in packing and transportation, it is easy to handle. Thus, the condenser of the present invention has a technical substance far more advanced than any conventional condenser and its industrial value is large.

While there has been described in connection with the preferred embodiment of this invention, it will be obvious

to those skilled in the art that various changes and modifications may be made therein without departing from the invention, and it is aimed, therefore, to cover in the appended claims all such changes and modifications as fall within the true spirit and scope of the invention.

5. What is claimed is:

1. A method of manufacturing condensers having discharge elements comprising placing a dielectric material having opposed surfaces in substantially parallel planes

10 between the substantially parallel arm portions of a U-shaped conductor near the curved portion thereof, covering the curved portion of said conductor and a portion of the substantially parallel arms adjacent said curved portion and at least a portion of the dielectric material disposed therebetween with a liquid insulating material capable of being hardened, hardening said insulating material and removing the curved portion of said conductor to expose the ends of said substantially parallel arm portions adjacent the end of said dielectric material to form

20 electrodes.

2. A method as claimed in claim 1, wherein the insulating material comprises a thermosetting resin.

3. A method as claimed in claim 1 wherein the covering of the curved portion of said conductor and a portion 25 of the substantially parallel arms adjacent said curved portion and a portion of the dielectric material disposed therebetween consists in dipping the portions into a bath of liquid hardenable insulating material for a predetermined adjustable distance to control the proportion of the dielectric material and conductor to be covered.

4. A method as claimed in claim 1 wherein the covering of liquid hardenable insulating material will produce, when hardened, a bond to anchor the electrodes securely 30 in close permanent contact with the dielectric material therebetween.

5. A method as claimed in claim 3 wherein that portion of the dielectric material disposed away from the curved portion of the conductor, before it is removed, is not covered by the liquid hardenable insulating material.
